US00D638055S

(12) **United States Design Patent**
Sato et al.

(10) **Patent No.:** **US D638,055 S**
(45) **Date of Patent:** **** May 17, 2011**

(54) **TONER CARTRIDGE**

(75) Inventors: **Fumikazu Sato**, Konan (JP); **Naoya Kamimura**, Ichinomiya (JP); **Nao Itabashi**, Nagoya (JP); **Hideshi Nishiyama**, Nagoya (JP)

(73) Assignee: **Brother Industries, Ltd.**, Nagoya (JP)

(**) Term: **14 Years**

(21) Appl. No.: **29/334,229**

(22) Filed: **Mar. 23, 2009**

(30) **Foreign Application Priority Data**

Sep. 30, 2008 (JP) 2008-025141

(51) **LOC (9) Cl.** **16-03**

(52) **U.S. Cl.** **D18/43**

(58) **Field of Classification Search** D14/471; D18/12, 36, 40, 43, 44, 56; 222/DIG. 1; 347/197, 222; 399/24-28, 107-112, 119, 399/121, 122, 222-224

(57) **CLAIM**

The ornamental design for a toner cartridge, as shown and described.

DESCRIPTION

FIG. 1 is a perspective view of a toner cartridge;
FIG. 2 is a front view thereof;
FIG. 3 is a top view thereof;
FIG. 4 is a right-side view thereof;
FIG. 5 is a left-side view thereof;
FIG. 6 is a rear view thereof;
FIG. 7 is a bottom view thereof;
FIG. 8 is another perspective view thereof;
FIG. 9 is a cross-sectional view thereof taken along the line 9—9 of FIG. 2; and,
FIG. 10 is a cross-sectional view thereof taken between the lines 10'—10' and 10"—10" of FIG. 3.
The broken lines depict environmental subject matter only and form no part of the claimed design.
